UNITED STATES PATENT OFFICE.

WILLIAM H. KLAUER, OF DUBUQUE, IOWA.

CULVERT.

1,082,878.

Specification of Letters Patent.

Patented Dec. 30, 1913.

Application filed April 21, 1913. Serial No. 762,504.

To all whom it may concern:

Be it known that I, WILLIAM H. KLAUER, a citizen of the United States, residing at Dubuque, in the county of Dubuque and State of Iowa, have invented certain new and useful Improvements in Culverts, of which the following is a specification.

My invention relates to culverts.

More particularly my invention relates to a nestable culvert.

The object of my invention is to produce culvert sections susceptible of union to any length desired without the use of bolts, rivets, or clamping bands.

A further object of my invention is to provide attachment and placement flanges at and adjacent respectively, overlying edges of semi circular sections (two or more) adapted to be united to form a cylindrical body.

In the drawings: Figure 1 is a side elevation showing a number of sections connected together and one member, detached. Fig. 2 is a section on the line 2-2 of Fig. 1, showing the form of section and interlocking means to accomplish relative placement before being interlocked, Fig. 3 is a section on the line 3-3 of Fig. 1, showing sections as in Fig. 2, placed in proper relation and interlocked, and, Fig. 4 is a sectional view, showing the manner of interlocking the cylindrical sections at their ends.

Longitudinal division of cylindrical culvert sections for nesting purposes is old; corrugating such sections is very old; and likewise lateral flanges both circumferential and longitudinal of culvert sections is old; and I do not claim invention therefor.

In my experience in the manufacture of culverts I have found it impossible to make a bend transverse of the corrugations to provide flanges without destroying, to a very considerable degree, such corrugations circumferentially of the sections and almost entirely in the lateral flanges, and without wholly destroying the galvanizing at the point of bending. The fact is that those who have produced integral flanged corrugated culvert sections have recognized the disadvantages named and have sought to minimize such disadvantages by bending as little as possible, the result being that instead of the faces of the flanges meeting, only their extreme outer edges are brought in contact, thus leaving a V space between the flanges.

In forming the culvert of my invention, I do not flange the longitudinal edges of the sections but provide flanged strips attachable to the sections, and flanges wholly coinciding when attached when the half sections are placed together.

Referring to the accompanying drawings, 2 are corrugated culvert sections, each section forming substantially one-half of a cylinder formed by the union of two sections, their longitudinal edges 3 and 4 being adapted in their proper union, to overlie each other and to be joined in the manner hereinafter described. To provide for an interlock between the ends of the sections, one corrugation may be made to overlie that of the adjacent section in such a manner that no bolts or rivets need be used.

7 are angle strips or plates, the flanges 7^a of which are corrugated to conform to the corrugations of the sections and are adapted to be riveted preferably to the sections, as shown, one end of the strip in conformity with the edge of one end of the section and the other end terminating approximately at the trough portion of the final corrugation at the other end of the section, and are positioned relative to the longitudinal edges of said sections so that the angle points of the strips are in substantial alignment with the edges thereof. The flanges 7^b of the angle strips 7 are disposed laterally of the section.

8 are flanged strips or plates having corrugated angle portions 8^a and laterally extended flat portions 8^b and upturned clamping portions 8^c. The corrugated portions 8^a of the flanged strips 8 are adapted to be riveted to the lower sections at the rear of the longitudinal edges thereof. Flanges 8^c are placed in spaced relation with the longitudinal edges of said sections. The flanged strips 7 and 8 are so formed and placed relatively that flange 7^b will seat upon flange 8^b with the edges of the sections 2 overlying each other and the outer edge of flange 7^b lying in contact relation with the upturned portion of flange 8^c.

In building a culvert from the sections, 105 those designed to form the upper and lower sections are placed relatively to interlock, as shown in the drawings, the upper sections having the laterally extending flanged portions 7^b being placed upon the lower sections with the flanged portions resting upon the laterally extending flanged portions 8^b.

of flanged plates 8 and then the edges 8^c may be bent downward into the position shown in Fig. 3 or they may be simply struck inwardly toward the body of the culvert, thus forming a secure interlock.

If desired, culvert sections, that is the upper and lower sections, may be arranged in break-joint relation with the same good results attending and without any modification in form, principle, or construction from that herein disclosed.

In the drawings I have shown flanged strips 7 and 8 upon the joined cylindrical sections overlapping slightly and in practice I prefer this form. However, in practice, the strips may be made to abut endwise, with good results and without departing from the spirit of my invention.

Having thus described my invention, what I claim is:—

1. As an improved article of manufacture, a pair of corrugated culvert sections adapted to be united to form a substantially cylindrical body with longitudinal edges respectively of the sections designed to overlie each other, a pair of angle strips disposed one upon each edge of one section and extending longitudinally thereof, a pair of angle strips disposed upon and in rear of each edge of the matching section longitudinally thereof provided with upturning locking flanges.

2. A substantially cylindrical culvert section comprising two members, one disposed above the other, an interlock for said members comprising pairs of angle strips, one pair disposed at the longitudinal edges of one section and the other pair at and in rear of the longitudinal edges of the other section, the latter having upturned members adapted to be struck over in contact relation with the flanges of the first named section.

3. In combination, semicylindrical sections adapted to be disposed relatively one above another and with their longitudinal edges overlying each other, sets of angle strips for each section secured respectively one angle strip of one set at each longitudinal edge of one section, and strips of the other set at and in rear of the edges of said section.

4. A culvert, comprising two sections, their longitudinal edges overlying each other, two sets of angle strips, one at the edge of one section and the other at the edge and in the rear of the other section, portions of said angle strips being folded together edge to edge and lip to lip.

In testimony whereof I have affixed my signature in presence of two witnesses.

WILLIAM H. KLAUER.
